UNITED STATES PATENT OFFICE

GEORGE H. BECKER, OF BRIDGEPORT, CONNECTICUT, ASSIGNOR TO THE BRIDGEPORT COACH LACE COMPANY, OF BRIDGEPORT, CONNECTICUT, A CORPORATION OF CONNECTICUT

DESIGN FOR A NARROW WEBBING

Application filed October 29, 1932. Serial No. 45,636. Term of patent 3½ years.

To all whom it may concern:

Be it known that I, GEORGE H. BECKER, a citizen of the United States, residing at Bridgeport, county of Fairfield, State of Connecticut, have invented a new, original, and ornamental Design for a Narrow Webbing, of which the following is a specification; reference being had to the accompanying drawing, forming part thereof.

The figure is a plan view of a narrow webbing, showing my new design.

I claim:

The ornamental design for a narrow webbing substantially as shown.

GEORGE H. BECKER.
